GASOLINE CONDENSER, STABILIZER, FRACTIONATOR, AND DEHYDRATOR

Filed June 20, 1927

UNITED STATES PATENT OFFICE

HELMUTH R. OTTO, OF SANTA PAULA, CALIFORNIA

GASOLINE CONDENSER, STABILIZER, FRACTIONATOR, AND DEHYDRATOR

Application filed June 20, 1927. Serial No. 199,984.

My invention relates to an apparatus for condensing, stabilizing, fractionating and dehydrating gasoline. While the apparatus is of general application and may be used in connection with any gasoline, it is especially intended in connection with the treatment of so-called casing head gasoline.

Casing head gas contains condensable hydrocarbon vapors which, in the general practice, are made to pass first through an absorbing medium such as distillate of mineral oil, known in the trade as seal oil, which absorbs condensable as well as incondensable hydrocarbons. The charged absorbing medium is then subjected to distillation to recover casing head gasoline. The ordinary casing head gasoline has a high specific gravity but is objectionable because of its highly volatile properties, which not only cause enormous losses through evaporation but increase greatly the danger of fire hazard. Therefore, methods and apparatus have been devised to subject the casing head gasoline to a blending and stabilizing treatment, having for its object to remove the incondensable hydrocarbons which are dissolved in the gasoline and to produce a more stable, less volatile motor fuel of lower specific gravity.

It is an object of this invention to provide an apparatus whereby such gasoline may be treated in order to produce a stabilized superior motor fuel from casing head gasoline which will compare favorably with gasoline produced by other methods.

My invention consists of the arrangement and construction of parts hereinafter described and claimed. Referring to the accompanying drawings which form a part of the specification:

Figure 1 is a vertical elevation in section of an apparatus embodying my invention.

Figs. 2, 3 and 4, are horizontal cross sections taken on the lines 2—2, 3—3 and 4—4, respectively of Fig. 1.

In the drawings 1 indicates a suitable base supporting a cylindrical shell 2. The same is divided into a lower or gasoline collecting chamber 3, an upper gasoline inlet chamber 40, and an intermediate reaction zone 4, by means of horizontal partitions 5 and 17.

The reaction zone 4 is divided into a plurality of reaction chambers by means of cylindrical sections 6, 7, 8 and 9, somewhat smaller in diameter than the outer shell 2 and concentrically spaced therefrom, providing annular chambers 10, 11, 12 and 13. The lower cylindrical section 6 rests upon the partition 5 and the cylindrical sections 7, 8 and 9, rest each respectively on horizontal partitions 14, 15 and 16, which are circular in shape and fit snugly against the inner walls of the shell 2, the partition 17 resting on the top of the top-most cylindrical section 9. Immediately below the partitions 14, 15, 16 and 17, is some suitable packing 111 which may be made of asbestos, forming a substantially fluid tight closure between the cylindrical sections and the outer shell 2.

Secured to and approximately midway in each cylindrical section 6, 7, 8 and 9, are partitions 18, 19, 20 and 21, dividing the space of each cylindrical section into upper and lower chambers which are designated as 22, 23, 24, 25, 26, 27, 28 and 29. To distinguish these two sets of chambers, the odd numerals will be referred to as gasoline receiving chambers and the even numerals as gasoline vapor chambers. All the partitions 5, 14 to 21 inclusive, are provided with a large number of perforations 30 clearly shown in Figs. 2, 3 and 4. These perforations are preferably circular in shape. Those in partition 17 are 7/64 inch in diameter, the perforations in partitions successively increasing 1/64 inch in diameter downwardly in the lower partitions for a purpose hereinafter explained.

Centrally located on partitions 18, 19, 20 and 21, are circular seal pans 31 having the top edge preferably serrated as at 32. These pans form liquid seals for gasoline passing from the chamber immediately above by means of conduits 33 whose lower ends extend below the top of the seal pans 31 but are spaced from the bottom thereof. The upper ends of gasoline conduits 33 project through the partition immediately above and are provided with funnel shaped mouths 34.

Each of the chambers 23, 24, 25, 26, 27, 28 and 29, is provided with a series of ports arranged in a circle in the walls of the cylin-

drical sections 6, 7, 8 and 9, and spaced from the partition immediately below. There is also a gasoline conduit 37 from the lowermost partition 5, to the lower end of which is fastened a seal pan 38, there being outlet ports 37' conducting the gasoline from 37 into seal pan 38.

The operation is as follows:

Hydrocarbon vapors coming from a still, not shown, in which the absorbent medium charged with casing head hydrocarbons is subjected to distillation, enter the lower part of the shell 2 immediately below partition 5 by means of an inlet pipe 39. These vapors have a temperature of about 200° F. and are of a pressure of twenty to thirty pounds. These hydrocarbon vapors pass upwardly through the apparatus as follows; they pass upwardly through all the perforated partitions, passing successively through the chambers 23 to 29 inclusive, thence through perforated partition 17 into the top chamber 40. During its passage all the condensable hydrocarbon vapors are dissolved in the cool condensing and blending medium which is preferably gasoline with which it has been brought into intimate and repeated contact during its passage through the apparatus. The incondensable fractions of the vapors pass out through the outlet pipe 41 of the apparatus and may be used as fuel if desired.

Gasoline, which may have a temperature from 50 to 70 degrees F., is introduced into the apparatus, being supplied by a valved pipe 42 through pump 50 and pipe 51, which enters a cooler 43 of any preferred or suitable construction, through inlet pipe 44 into the top chamber 40. Though all the horizontal partitions 5, 18, 14, 19, 15, 20, 16, 21 and 17, are perforated, practically no gasoline will percolate through them due to the fact that the vapors passing in the opposite direction upwardly through the apparatus are under considerable pressure and prevent any appreciable amount of gasoline from flowing through the perforations. The pressure of the vapors as they are cooled in their upward passage gradually decrease and, therefore, the size of the perforations 30 in the partitions decrease successively upwardly in the partitions, the object being to prevent any appreciable flow of the gasoline through these perforations by allowing the vapors to pass upwardly therethrough. The gasoline will build up to a level until it overflows into the top most gasoline conduit 34, flowing into the compartment 29 immediately below. The gasoline will flow over the edge of the seal pan 31 and then through ports 35 into the annular chamber 13, thence inwardly through ports 35 and again through the gasoline conduit 34.

In this manner the gasoline is forced to take a path passing from chamber 40 to chamber 29, thence through annular chamber 13

into chamber 28, then through gasoline conduit 34 to chamber 27 immediately below, then again to the annular chamber 12, thence to chamber 26, chamber 25 immediately below, annular chamber 11, chamber 24, chamber 23 immediately below, and annular chamber 10, chamber 22 immediately below, and thence through the gasoline conduit 37 to seal pan 38 from which it overflows into the gasoline collecting chamber 3.

In this manner the gasoline is brought in repeated intimate contact with the vapors passing in the opposite direction, condensing, vaporizing, fractionating and blending the same. The temperature of the gasoline in the gasoline cooling chamber 3 ranges from 90 to 130 degrees F. After the initial supply of the gasoline introduced through supply pipe 42, the gasoline cooled in chamber 3 may be used, closing the valve in pipe 42 and opening the valve in outlet pipe 45. The gasoline is thence passed to the chamber 40 and the cycle of operation is repeated to produce a stabilized motor fuel. The quantity of gasoline recovered will, of course, increase and is taken off periodically through the main gasoline outlet pipe 46 leading from chamber 3. Water of condensation collecting in the bottom of chamber 3 may be removed periodically through outlet pipe 47.

It should be noted that the construction of the apparatus is very simple. It may be easily assembled or taken apart for repairs for the reason that the cylindrical sections 6, 7, 8 and 9, are units having their inside partitions 18, 19, 20 and 21, formed integral therewith. These cylindrical sections rest loosely upon partitions 5, 14, 15 and 16, none of which are fastened to the shell, and they, together with the partition 17 at the top, may be removed by merely taking off the head of the shell 2.

Various changes may be made in the construction and arrangement of parts without departing from the spirit of my invention as claimed.

I claim:

1. In an apparatus of the class described, the combination of a vertical cylindrical shell having a gasoline collecting chamber at the bottom and a gasoline inlet chamber at the top, a series of superimposed reaction chambers having perforated bottoms intermediate the ends of said shell, a series of superimposed annular chambers between said reaction chambers and said shell, said reaction chambers being provided with means for conducting gasoline alternately through the said reaction chambers and said annular chambers in the downward direction, means for conducting gasoline successively downwardly through said reaction chambers, means for conducting gasoline vapors successively upwardly through said reaction chambers, a conduit connecting said gasoline collecting

chamber with the gasoline inlet chamber, and a cooler in said conduit.

2. In an apparatus of the class described, the combination of a vertical outer cylindrical shell having a gasoline collecting chamber in the lower part thereof and a gasoline inlet chamber at the upper part thereof, a series of cylindrical sections of smaller diameter than the said outer shell, said sections disposed within said shell and spaced therefrom, a series of horizontal partitions extending entirely across said outer shell disposed between said cylindrical sections, a similarly constructed partition engaging the bottom of the lower-most cylindrical section, another of said partitions engaging the top-most cylindrical section, each of said cylindrical sections being provided with a horizontal partition intermediate its ends and integral therewith, all of said partitions being perforated within the plane of said cylindrical sections, said partitions forming with the cylindrical sections a series of superimposed reaction chambers, each of said larger partitions being provided with a gasoline conduit conducting gasoline from the chamber immediately above to the chamber immediately below, each of said chambers being provided with a series of ports equi-distantly spaced from the partition immediately below, a conduit connecting the gasoline collecting chamber with the gasoline inlet chamber, and a cooler in said conduit.

In testimony whereof I have signed my name to this specification.

H. R. OTTO.
